UNITED STATES PATENT OFFICE.

NATHAN L. GRIFFIN, OF WOODWARD, OKLAHOMA.

PAPER-CLIP.

1,151,943.

Specification of Letters Patent. Patented Aug. 31, 1915.

Application filed September 9, 1913. Serial No. 788,922.

To all whom it may concern:

Be it known that I, NATHAN L. GRIFFIN, citizen of the United States, residing at Woodward, in the county of Woodward and State of Oklahoma, have invented certain new and useful Improvements in Paper-Clips, of which the following is a specification.

This invention relates to paper clips and 10 has as its object to provide a clip which may be more readily manipulated than the clips now in common use; will be equally as inexpensive to manufacture; and adapted for application to the papers to be held without 15 the exercise of any particular attention or care.

The invention has as one of its objects to provide a clip which may be applied in either one of two positions and in which the 20 gripping fingers are so arranged that when the clip is grasped between the fore and middle fingers and the thumb the fingers will be slightly sprung so as to readily accommodate the sheets to be held.

25 Another feature of the invention resides in so constructing the clip that its portions at opposite sides of a median line will be of counterpart form so that the clip may be applied either end first with the fingers 30 gripping the leaves throughout the entire length of the fingers.

A further feature of the invention resides in the fact that the general form of the clip is such that its length may be increased if 35 found desirable for the purpose of providing a greater gripping surface, without, however, in any way changing the form of the clip.

In the accompanying drawings: Figures 40 1, 2, 3 and 5 illustrate the clip applied in a number of different ways; Fig. 4 is a view in elevation of the clip.

Corresponding and like parts are referred to in the following description and indicated 45 in all the views of the accompanying drawing by the same reference characters.

In the drawings the clip is illustrated as formed from a single length of resilient wire bent so as to provide a number of gripping fingers 1 which are alternately extended in opposite directions and from opposite sides of the clip, the intermediate loops being semi-elliptical and the end loops being elliptical. In forming the fingers 1 the sides 50 of the intermediate fingers are also the sides of the end fingers and it will be observed 55 that the bends forming the clip are of even number so that the free ends of the fingers will be equal in number at the top and bottom of the clip. Considering the upper and 60 lower ends of the clip as opposite sides thereof it may be stated that the fingers alternately project from opposite sides of the clip and it will be observed that the terminals of the wire of which the clip is 65 formed are returned as indicated at 2 so as to form auxiliary gripping portions or fingers and that the extremities of the returned portions approximately touch the horizontal median line of the clip as indicated by the dotted line α — α of Fig. 4. It will furthermore be observed from the drawing that the fingers are of equal length as are also the gripping portions 2 and that regardless of which end of the clip is first 70 applied to the sheet to be held, the fingers lying upon opposite sides of the sheets will grip the same throughout the entire lengths of the fingers and throughout the entire 75 lengths of the terminal portions which are 80 bent to form the gripping portions 2. Furthermore, it will be noted that the gripping portions 2 are located at opposite sides of the horizontal median line α — α so that the portions of the clip at the opposite sides 85 of this line are of counterpart form. Furthermore, it will be apparent that the terminal portions of the clip are free or open so that no obstruction whatsoever is offered to the insertion of leaves between one of the 90 fingers and one gripping portion 2 on one side and the other or intermediate finger on the other side.

Referring now to Fig. 1 of the drawing it will be observed that the clip has been applied in such manner that one of the fingers 95 bears against one side of the sheet or sheets to be held and the gripping portion 2 next adjacent thereto together with the other finger and its adjacent gripping portion 100 bear against the other side of the said sheet or sheets. The clip is applied in substantially the same manner in Fig. 2 of the drawing except that the finger next adjacent the finger first mentioned in describing the 105 application of the clip in Fig. 1 together with both of the gripping portions 2 bears against the face of the sheet with the finger first mentioned in connection with Fig. 1 bearing against the obverse side of the sheet. 110 In Fig. 3 the clip is applied as in Fig. 2 except in reversed position or more specifi-

cially speaking, with its portions which bear against the obverse side of the sheet in Fig. 1, bearing against the face of the sheet in Fig. 3 and vice versa.

Having thus described the invention, what is claimed as new is:

A paper clip formed from a length of wire bent to form semi-elliptical intermediate loops and elliptical end loops, the intermediate loops being of equal number at opposite sides of the horizontal median line of the clip, and the terminal loops also lying at

opposite sides of the said horizontal median line, the extremities of the wire forming the clip being in the horizontal median line thereof and resting against the sides of the adjacent intermediate loops, said extremities and all the loops lying in a plane. 15

In testimony whereof I affix my signature in presence of two witnesses.

NATHAN L. GRIFFIN. [L.S.]

Witnesses:

J. O. LITTLE,
G. W. WELCH.
